OTTO E. TRAUTMANN, OF ROCHESTER, NEW YORK, ASSIGNOR TO BAUSCH & LOMB OPTICAL COMPANY, OF ROCHESTER, NEW YORK, A CORPORATION OF NEW YORK

DESIGN FOR A FIELD GLASS

Application filed December 15, 1930. Serial No. 38,001. Term of patent 14 years.

To all whom it may concern:

Be it known that I, OTTO E. TRAUTMANN, a citizen of the United States, and a resident of Rochester, county of Monroe, and State of New York, have invented a new, original, and ornamental Design for Field Glass, of which the following is a specification, reference being had to the accompanying drawing, forming a part hereof.

Fig. 1 is a top plan view of a field glass showing my new design.

Fig. 2 is a front elevation of same.

I claim:

The ornamental design for a field glass substantially as shown.

OTTO E. TRAUTMANN.
